Primary Examiner—A. Hugo Word**Assistant Examiner**—Lavone D. Tabor**Attorney, Agent, or Firm**—Weldon F. Green**[57]****CLAIM**

The ornamental design for a composite head and handle unit for a utensil, as shown and described.

DESCRIPTION

FIG. 1 is a perspective view of a composite head and handle unit for a utensil showing our new design;

FIG. 2 is a right side elevational view thereof, the left side being a mirror image of the right side;

FIG. 3 is a front elevational view thereof;

FIG. 4 is a top plan view thereof;

FIG. 5 is a bottom plan view thereof; and,

FIG. 6 is a cross-sectional view taken along line 6—6 of FIG. 5.

The broken lines are for illustrative purposes only and form no part of the claimed design.
